LAMP STANDARD AND FIXTURE

Van Nollen Marker, Evanston, and Davis
McMakin, Hinsdale, Ill., assignors to Re-
vere Electric Company, Chicago, Ill.

Application December 19, 1933, Serial No. 703,144

7 Claims. (Cl. 248—159)

This invention relates to lamp standards and more particularly to a standard such as employed in gasoline service stations, and for the purpose of replacing the light bulbs, cleaning, etc.

5 the standard includes a hinge joint intermediate its height, permitting the upper portion of the standard to be swung into close proximity to the base upon which the standard is erected.

It is an object of the invention to provide a 10 novel and simple construction of hinge joint which will accommodate the electrical wires for the lamps carried within the standard, without liability of setting up wear upon the insulation of the wires during breaking of the hinge joint, 15 and to further provide a hinge structure wherein the electrical wires may be readily threaded therethrough during assembly of the standard or for the purpose of replacing the wires.

It is a further object of the invention to provide 20 a standard of the type set forth wherein the abutting ends of the standard are so constructed as to permit the standard to break the joint in only one direction of movement; and further to provide novel means for locking the 25 swinging portion of the standard against movement.

It is a still further object of the invention to provide a swinging standard of the type described wherein sign supporting arms may be readily 30 incorporated with the standard without liability of interference during "breaking" action of the standard, and wherein the signs may be adjusted to varying angles, as desired.

Additional objects, advantages and features of 35 invention will be apparent from the following description and accompanying drawings, wherein

Figure 1 is a side elevation of a standard construction in accordance with my invention.

Figure 2 is a fragmentary elevation, at right 40 angles to Figure 1.

Figure 3 is a vertical sectional view on the line 3—3 of Figure 1.

Figure 4 is a vertical sectional view on the line 4—4 of Figure 3.

45 Figure 5 is a fragmentary perspective view illustrating the locking means for the swinging standard.

Figure 6 is a side elevation of a standard equipped with arms for support of signs or the 50 like.

Figure 7 is a cross section on the line 7—7 of Figure 6.

Figure 8 is a cross section of one of the supporting arms, taken on the line 8—8 of Figure 55 9.

Figure 9 is a cross section on the line 9—9 of Figure 6.

Figure 10 is a modification of the standard mounting.

Figure 11 is a fragmentary sectional view of 5 one of the bracket supporting arms.

In carrying out our invention, we provide a main standard 10 adapted to be supported in an erect position by having its base end secured in a foundation of concrete 11, or otherwise as desired. The standard 10, as shown in the present instance, is formed from hollow square tubing, and may be of any suitable length, and in practice the standard 10 has been made approximately 14 feet in length from its base end to 15 the hinge joint of the completed standard, although such dimension may vary to suit the particular lighting problem involved.

Adjacent the base of the standard 10 there is a hole, suitably tapped to receive a conduit 12, 20 and through this conduit electric wires 13 are fed, which continue through the standard 10 to the light as will be presently explained.

As clearly shown in Figures 1 and 4, the standard 10 terminates at an angle of approximately 25 45 degrees, defining an inclined face 14. A suitable distance downwardly from the face 14 the standard is provided with apertures 15 formed in opposed walls of the standard defining bearings for a swinging standard 16, as will now be 30 fully described.

The standard 16 is formed from square tubing similar to that employed in the standard 10, but of slightly less dimensions, and terminates at its upper end with any suitable fitting for support 35 of a conventional form of floodlight, generally indicated at 17.

The lower end of the standard 16 is cut at an angle similar to the angle of the standard 10, defining a face 18. When the standard 16 is in its 40 normal erect position, the faces 14 and 18 of respective standards will be in snug abutting relation and in such position, it will be apparent that the standard 16 may be swung in one direction only, as will be more fully set forth hereinafter. 45

Upon the outer faces of opposed sides of the standard 16 there are arms 19, which, as shown are welded or otherwise secured to the standard 16. Thus, the arms 19 provide a yoke, generally indicated at 20, the arms being so spaced as to receive the standard 10 freely therebetween, but at a point in close proximity to the hinge joint of the standard, we prefer to have a frictional contact between the arms 19 and the standard 10, thus providing a non-shaking assembly. The arms 19 50 55

may have any suitable length, but preferably they extend downwardly upon the standard 10 to a height approximately 6 feet 6 inches from the base of the standard 10, where they are connected by a flat integral bridge member 21. The bridge member 21 is apertured and receives therethrough a threaded bolt 22 carried by the standard 10 and in order to maintain the swinging standard 16 in its erect position there is provided a nut 23 co-operable with the bolt 22, the nut having bearing contact with the bridge member 21. Unauthorized persons may not release the swinging standard 16, since the bolt 22 has an aperture therethrough, within which any suitable lock 22' may be engaged, preventing removal of the nut 23. The yoke 20 may be suitably reinforced by bridge members 21' similar to the bridge 21, in order to insure a proper relationship between the two arms 19.

Reference is now made particularly to Figures 3 and 4 of the drawings for a clear understanding of the hinge joint between the standards 10 and 16, generally indicated at H. Each of the arms 19 are provided with aligned apertures 24 adapted to register with the apertures 15 of the standard 10 and through these aligned apertures a bolt 25 is inserted. The bolt 25 has a flanged head 26 having unequally spaced apertures and the adjacent arm 19 is similarly apertured and tapped to receive machine screws 27. Thus, the flanged head of the bolt may be snugly held in place against the adjacent arm and rotation of the bolt is prevented; and due to the unequal spacing of the screw apertures, the bolt 25 may only be installed in one position, for a purpose which will presently appear. The end of the bolt 25 opposite the head 26 terminates flush with the adjacent arm 19, and an axial bore 28 is formed in the bolt 25 opening upon the end opposite the head and stopping short inwardly thereof a short distance. An arcuate slot 29 is formed in the bolt 25 at right angles to the bore 28 and opens upon the hollow standard 10 and disposed in a direction to receive the wires 13 extending upwardly from the base 11. From the foregoing description, it will be understood that the wires 13 are threaded through the opening 29 and thence the bore 28 exteriorly of the adjacent arm 19. The last named arm and the standard 16 are provided with aligned apertures 30 forming communication with the interior of the hollow standard 16, and through these aligned apertures the wires 13 are passed so that they may be carried upwardly through the standard to the floodlight 17. The provision of the slots 29 permits swinging movement of the standard without distortion of the electrical conductors.

It will be noted that the wires 13 do not pass directly from the standard 10 to the standard 16, but are disposed for a short distance upon the exterior surface of the arm 19 by reason of which the wires are relieved of wear during "breaking" of the joint. It is desirable, however, that some form of covering be provided for the wires where they pass from one standard to the other, and we therefore provide a cover plate 31. The plate 31 is of cupped formation which, when bolted to the arm 19 by screws or the like, provides a passage 32 readily housing the wires against exposure to the elements. If desired, a gasket may be employed between the plate and the arm 19. The construction described also presents a simplified means for replacing wires as occasion demands, obviating the need for dismantling the standard, as would otherwise be the case.

From the foregoing, it will be apparent that with removal of the lock 22' and the nut 23, the arms 19 will swing to the dotted line position shown in Figure 1, due to the weight of the floodlights 17, positioning the floodlights at such height that the electric bulbs contained therein may be readily replaced, cleaned or otherwise, by an attendant standing at the base of the standard. It will be noted that the standard 16 will be permitted to swing in one direction only, due to the abutting faces 14 and 18, and these faces in conjunction with the bridge 21 prevent movement in a reverse direction beyond a true erect position of the standards, which is essential when returning the standard 16 to its operative position. The "breaking" action of the hinge joint and swinging movement of the standard 16 may be controlled by means of a chain 33 secured to the bridge member 21. The chain 33 is also employed to swing the standard 16 to erect position, so that the bridge member 21 will align with the bolt 22. When the standard 16 has been swung to such position, the nut 23 is screwed into position upon the bridge member and the lock 22' secured in the bolt 22.

In Figures 6 to 9, we have shown a modification of the standard, wherein sign supporting arms are incorporated with the standard. The standard is constructed as described in the first form, with the exception of the lower standard 10, which will now be described. The standard 10, as clearly shown in Figure 7, is constructed from a hollow square casing as before described, and within this casing there is a cylindrical pipe 35 which in practice has been spot welded to the shell, at suitable points. The pipe 35 is of a length to extend from the base of the standard casing to a point slightly above the hinge joint, and it will be readily apparent that a standard thus constructed will have ample rigidity for support of advertising signs, many of which are of considerable weight.

Upon the standard 10, slightly below the hinge joint H there are mounted a pair of arms 36 and 37 disposed transversely of the standard and arranged in superposed relation, as clearly shown in Figure 6. These arms are preferably formed of cast steel and are welded to the standard 10 upon a side thereof which will permit free swinging movement of the arms 19 of the standard 16. The arm 37 is provided at its ends with apertures 38, and the arm 36 has formed at the extremities thereof recessed seats 54 in alignment with respective apertures 38. Through respective apertures and engaged upon the seats there is positioned a leg 39 of a sign supporting bracket arm 40. It will be noted that the leg members are vertically arranged upon opposite sides of the standard 10, and that the bracket arms 40, which are in the present instance shown as continuations of the leg members, are extended at right angles thereto. The bracket arms are of a length to afford ample support for advertising signs, as will be explained hereinafter.

The legs 39 are adjustably retained within the arms 36 and 37, so that signs supported from the bracket arms 40 may be swung to various angles with respect to the standard, as indicated in dotted lines in Figure 9. In order to secure the leg members 39 in fixed adjusted positions, the arms 36 and 37 opposite respective apertures 38 are drilled and tapped to receive set screws 41 which will impinge upon the leg members 39.

Any suitable sign elements may be suspended from the arms 40, and in the present instance 75

- we have shown circular disk elements 42 supported from the arms 40 by hangers 43. These signs will carry advertising matter upon opposite sides thereof and to make these signs discernible
- 5 at night, the arms 40 are each provided with a pair of oppositely disposed brackets 44 supporting lamps 45. The sign elements being thus suspended in such manner that both sides thereof are fully illuminated from the lamps 45.
- 10 Various constructions may be employed for securing the brackets 44 to the arm 40, but we have illustrated a preferred form in Figure 8. In this form, we have shown a fitting 46 having opposed nipples 47 into which the arms 44 are secured. The fixture 46 in the present instance is of hollow formation, and comprises a saddle 48 having a semi-circular recess of a size to snugly seat upon the arm 40, and medially of the saddle 48, the fixture 46 has a downwardly turned 20 throat 49 adapted to engage within an aperture 50 formed in the arm 40. The fixture 46 is clamped in position upon the arm 40 by a clip 51. From the foregoing, it will be apparent that the electrical conductors carried by the arms 40 may be readily threaded through the throat 49 and thence through respective bracket arms 44 to the lamps 45, which may be facilitated by removal of the cover plate 52. It will be apparent that the throat 49 engaged within the aperture 50 of the 25 arm 40 acting in conjunction with the clip 51, the fixture 46 will be positively held against oscillations or other movements and a secure connection between the arm 40 and bracket arms 44 is established.
- 30 Attention is now invited particularly to Figures 7 and 11 of the drawings for further discussion of the construction of the arm 36. As has been previously stated, the arm 36 is welded to the standard 10, and since this arm in addition to providing a pivot for the legs 39, defines a conduit for the electrical conductors, the arm is hollow, providing a channel 53 opening upon the seats 54. The arm 36 is also provided upon opposite sides with openings 55 and 55', the former 35 opening registering with aligned apertures 56 and 57 formed in the standard 10 and tube 35, respectively. The latter opening 55' which is upon the exposed side of the arm constitutes ready means for gaining access to the wires for 40 threading the same through the various apertures of the fixture and is closed normally by the cover plate 58. At the lowest point of the arm 36, a drainage aperture 36a is provided.
- 45 The electrical conductors are threaded through the standards 10 and 16 as in the first form herein described, but at a suitable point, the conductors 13 are tapped by wires extending from the lamp fixtures 45, such wires being threaded through the bracket arms 44, the arms 40, the 50 legs 39 downwardly through the seats 54, the channel 53 and thence through aligned apertures 55, 56 and 57.
- 55 In Figure 10 a modified form of base is shown, which may be found desirable in certain installations. In this instance, the standard 10 is provided with a foot 59 adapted to seat flush upon a supporting surface. The foot comprises a flat base 60, connected as an integral part of the standard by fins 61. The base 60 is suitably apertured and through each aperture there is engaged an anchor bolt 62 which may be embedded in concrete or otherwise. In the construction described, it is also intended to feed the electrical conductors directly through the base 60, as indicated by the conduit 63, and in order to facilitate

splicing of the electrical conductors an aperture 64 is provided in the standard 10. A plate 64' may be employed to close the aperture, as shown.

While we have shown and described certain preferred constructions we are well aware that the ends attained thereby may be accomplished by modifications of the structures set forth, and therefore we consider as our own all such modifications as fairly fall within the scope of the appended claims.

We claim:

1. In an electrical fixture, a hollow conduit, a hollow fixture member associated therewith and having leg members disposed about said conduit, a hollow bolt extending transversely through said leg members and the conduit, defining a pivotal connection therebetween, said hollow bolt having an opening in communication with the conduit, a flexible conductor housed within the conduit and threaded through the opening of the bolt to extend longitudinally therethrough to a point exteriorly of one of the leg members, and said fixture member having an aperture opening upon one side thereof, through which the flexible conductor is threaded to position the same within the hollow fixture.

2. In an electrical fixture, a hollow conduit, a hollow fixture member associated therewith and having leg members disposed about said conduit, a hollow bolt extending transversely through said leg members and the conduit, defining a pivotal connection therebetween, said hollow bolt having an opening in communication with the conduit, a flexible conductor housed within the conduit and threaded through the opening of the bolt to extend longitudinally therethrough to a point exteriorly of one of the leg members, the fixture member having an aperture opening upon one side thereof, through which the flexible conductor is threaded to position the same within the hollow fixture member, and a closure member mounted upon the leg member to house the conductor positioned exteriorly of the leg member.

3. In an electric lamp standard, a support member and a fixture standard arranged in end to end relationship, said fixture member having a pair of leg members spaced to receive the support member therebetween, a pivot bolt passed transversely through the leg members and said support, said bolt having a longitudinal bore opening upon one end thereof and an aperture opening upon said bore at right angles thereto, and a flexible conductor carried by the support member, threaded through said aperture and bore and supported by said fixture member.

4. In an electric lamp standard, a stationary hollow standard, a hollow fixture member associated therewith and having leg members disposed upon the hollow standard, a pivot bolt extended transversely through the leg members and the standard for pivotal mounting of the fixture member, said bolt having a longitudinal bore opening upon one end thereof and further having an aperture formed therein at right angles to the bore and opening upon the interior of the hollow standard, said fixture member having an aperture opening upon one side thereof, and a flexible conductor carried within the hollow standard, threaded through the aperture and bore of the pivot bolt and through the aperture of the fixture member to position the conductor within the hollow fixture member.

5. In an electrical lamp standard, a stationary

hollow standard, a hollow fixture member associated therewith and having leg members disposed upon opposed sides of the hollow standard, a pivot bolt extended transversely through the leg members and the standard for pivotal mounting of the fixture member, said bolt having a flat head member snugly abutting one of the leg members, fastening means between said head and abutting leg for maintaining said bolt against movement, the bolt further having a longitudinal bore and an aperture formed at right angles thereto, a conductor housing carried by said other leg member in communication with the bore of the bolt, an aperture formed in said fixture member establishing communication with the conductor housing, and a flexible conductor threaded through the bolt and conductor housing and extended longitudinally through the hollow standard and fixture member.

10 6. In an electric fixture, a stationary member

and a swinging member, said swinging member having parallel legs spaced to receive the other member in end to end relation, a hollow pivot extending through the legs and the member interposed therebetween, and a flexible conductor extending through the stationary and swinging members and the hollow pivot.

15 7. In an electrical fixture, a stationary member and a swinging member, said swinging member having parallel legs spaced to receive the other member in end to end relation, a hollow pivot extending through the legs and the member interposed therebetween, a flexible conductor carried within the stationary member and extending longitudinally through the pivot to a point exteriorly of the stationary and swinging members and thence to a point interiorly of the swinging member.

20 VAN N. MARKER.
DAVIS McMAKIN. 20
